PAGE 3

Fig. 5.

Fig. 6.

*Fig. 7.**Fig. 8.*FIG. 1 is a side elevational view of a combined portable electric can opener and knife sharpener attachment showing my new design;

FIG. 2 is an exploded top plan view thereof;

FIG. 3 is a side elevational view thereof with the knife sharpener attachment removed for convenience of illustration;

FIG. 4 is a front elevational view thereof with the knife sharpener attachment removed for convenience of illustration;

FIG. 5 is a front elevational view thereof;

FIG. 6 is a rear elevational view thereof;

FIG. 7 is a bottom perspective view thereof with the knife sharpener attachment removed for convenience of illustration of the side shown in FIG. 1; and

FIG. 8 is a top perspective view thereof with the knife

sharpener attachment removed for convenience of illustration of the side opposite to that shown in FIG. 7.

The electric power cord is fragmentarily shown for convenience of illustration; and

The operating lever is shown in its raised position in FIGS. 1, 2, 7 and 8 and its lowered position in FIGS. 3-6.

I claim:

The ornamental design for a combined portable electric can opener and knife sharpener attachment, as shown and described.
